DESIGN FOR SUNGLASSES

Jacques E. Maisch, New York, N. Y.

Application June 29, 1939, Serial No. 85,749

Term of patent 3½ years

To all whom it may concern:

Be it known that I, Jacques E. Maisch, a citizen of France, residing in the city of New York, county of New York, and State of New York, have invented a new, original, and ornamental Design for Sunglasses, of which the following is a specification, reference being had to the accompanying drawing, forming part thereof.

The figure on the drawing is a perspective view of sunglasses showing my design.

I claim:

The ornamental design for sunglasses, substantially as shown.

JACQUES E. MAISCH.
